(57) **CLAIM**

The ornamental design for a golf-club caddy, as shown and described.

DESCRIPTION

FIG. 1 is a right top front perspective view of a golf-club caddy having my new design;

FIG. 2 is a front perspective view thereof;

FIG. 3 is a rear perspective view thereof;

FIG. 4 is a right top rear perspective view thereof;

FIG. 5 is a bottom perspective view thereof;

FIG. 6 is a left top front perspective view thereof;

FIG. 7 is a left side elevational view thereof, the right side being a mirror image thereof with the exception of the handle adjustment lever which is as shown in FIGS. 1, 4, 5, 8 9, 13, 14 and 15;

FIG. 8 is a rear elevational view thereof;

FIG. 9 is a top plan view thereof;

FIG. 10 is front elevational view thereof with the golf-club caddy tilted rearwardly;

FIG. 11 is a front elevational view thereof with the golf-club caddy resting on the front support in the position as shown in FIG. 7;

FIG. 12 is top front elevational view thereof taken perpendicular to the incline of the longitudinal axis of the support tubes shown in FIG. 7.

FIG. 13 is a top front elevational view thereof taken between the view of FIGS. 9 and 12;

FIG. 14 is a top front elevational view thereof taken between the views of FIGS. 9 and 13; and,

FIG. 15 is a top rear elevational view thereof taken parallel to the incline of the longitudinal axis of the support tubes shown in FIG. 7.
